UNITED STATES PATENT OFFICE

2,238,230

APPARATUS FOR PRODUCING COPS

Wilhelm Reiners and Gustav Kahlisch, Gladbach-Rheydt, Germany, assignors to W. Schlafhorst & Co., Gladbach-Rheydt, Germany, a corporation of Germany

Application March 25, 1937, Serial No. 132,945
In Germany April 22, 1936

4 Claims. (Cl. 242—41)

In our copending application Serial No. 71,266, filed March 27, 1936, and our copending application, Ser. No. 182,690, filed December 31, 1937, which has now become Patent No. 2,209,208, winding machines are described for winding a group of cops, which automatically control the independent building of the cops, doffing of the cops and donning of the tubes at every winding point. The means for automatically supplying the tubes enable the tube to be wound to be taken from a magazine outside the winding point, to be swung into winding position, or the magazine to be so positioned with respect to the winding position that a tube is released therefrom from time to time and left in the winding position.

According to the present invention provision is made whereby short tubes (so called cop starting tubes or cones) may be used. To this end means are provided whereby after the tube to be wound has been swung in from the preparatory position to the winding position, with or without the magazine from which it is supplied, it is also movable axially in the winding position.

The invention will be described in detail by reference to the accompanying drawings, wherein we have shown one illustrative form of the same.

In the drawings

Fig. 1 is a side elevation, with portions in section, of a spindle and adjacent parts;

Fig. 2 is a front elevation of the same from the direction of the arrow in Fig. 1; and

Figs. 3 to 6 are simplified plan views of the same showing the parts in various positions of operation.

In the illustrative machine shown in the drawings, a spindle 4 is journaled in a bearing 5, and a tail stock comprising a rotary socket 220 is journaled on a post 221. The post 221 is slidably mounted on a shaft 222 and is connected to a rack bar 225 engaging a gear 226. The gear 226 is rotatably mounted upon a drive shaft 39 and can be coupled to said shaft from time to time as each cop is completed, by any suitable means, such as that shown in our aforesaid patent. The coupling means are not illustrated in the present application. The return movement of gear 226 may be caused by a weight, which is also not shown in the present application, but is shown in the said copending application. Movement of the gear 226 under the drive of shaft 39 causes the rack bar 225 to travel to the right in Fig. 1, while its movement under the influence of the weight brings it back toward the left. The shaft

222 is slidably mounted at the foot of bearing 5 and has fixed on its outer end a collar 223 by which it is carried to the right with the tail stock on its movement to the right under the drive of gear 226. To the left (Fig. 1) of the tail stock post 221 there is fixed to shaft 222 a post 219b bearing a doffing cup 219a, which embraces the spindle 4. The cup 219a has the function of doffing the completed cop, in manner to be described. The building of the cop is controlled by a cone 145, called a bell cone, mounted below the spindle 4 upon an inclined pin 144. The pin 144 projects rigidly from the end of a pivoted lever composed of two arms 143 and 141 and a journal 142 which mounts it in the frame of the machine. The arm 141 bears against a cam 140 fixed to the hub of gear 226, under the action of a spring 142a which urges the lever in counterclockwise direction, as seen in Fig. 2. The cop is started upon a short tube 10 mounted upon the spindle 4, the traverse of the thread being provided for by a thread guide 14a mounted upon a rock shaft 138a, which may be oscillated by any suitable means, such as that disclosed in the aforesaid copending application.

The tubes 10 are supplied to the spindle from a carrier 62 rockably mounted on the shaft 222. The lower end of carrier 62 is forked to embrace a long pin 146 fixed upon the end of an arm 62a rockably supported upon a stud 64. The hub of arm 62a has rigidly projecting downward from it an arm 63 bearing by pin 65 against a cam 66, which is rigidly secured to the hub of gear 226. A spring 64a applies a turning force to the lever 62a, 63, which holds pin 65 against cam 66. In the embodiment shown the carrier 62 has fixed to its upper end a magazine 147 comprising two bars held together by braces 147a to form a guide, engaging grooves at the base of cop tubes 10. The bottom cop tube is restrained by a spring-influenced latch 148.

The device operates in the following manner: The tube magazine 147 is supplied with tubes by hand, or from any suitable device, such as a special tube clip, from which they can be stripped off into the magazine 147. Alternatively the tube magazine 147 can be detachably mounted upon the carrier 62 so as to be supplied with tubes when dismounted and set in position on the carrier with its tubes in place. Assume that in the previous winding operation a cop has been fully wound, as shown in Fig. 3, and is ready to be doffed. As this time the magazine and carrier 62 stand at one side of the spindle. The growth of the cop has caused the tail stock 220, 221 to reach

a position abutting against collar 223. At this instant the doffing is initiated preferably by an automatic mechanism, such as that shown in our said Patent No. 2,209,208, by coupling gear 226 to shaft 39, so that the rack bar 225 is driven to the right (Fig. 1). At the start of the movement of the gear 226 the cam 140 tilts lever 141, 143, to one side, to clear the way for the operation of doffing cup 219a. As the rack bar 225 now moves outward, shaft 222, drawn by the hub of tail stock post 221 abutting against collar 223, is pulled to the right and doffing cup 219a engages the nose of the cop and pushes it off the spindle. The hub of carrier 62 is engaged by the hub of the post 219b on which cup 219a is mounted, so that the carrier 62 moves to the right with the doffing cup. It is therefore positioned beyond the end of spindle 4 at the close of the doffing operation. Cam 66 now comes into operation and rocks lever 62a, 63, clockwise (Fig. 2), thus rocking lever 62 counterclockwise and bringing the bottom tube 10 into alignment with the spindle 4. Shortly after, the gear and cam unit 226, 66, 140, is uncoupled from shaft 39 and begins its return rotation under the influence of the weight (not shown). The resulting movement of rack bar 225 to the left brings the hub of post 221 into engagement with the hub of carrier 62 and pushes the empty cop tube 10 onto spindle 4. Thereupon cam 66 releases lever 62a, 63, which swings back counterclockwise under the influence of spring 64a and withdraws the carrier 62 from the spindle, the donned tube slipping out from the spring latch 148 and allowing the set of tubes in the magazine to drop. At about this time the bell cone 145 is rocked back into operative position and the winding, which has been interrupted by the uncoupling of spindle 4 from its driving means preferably by a clutch device such as that disclosed in our said Patent No. 2,209,208, is re-commenced.

We claim:

1. In a cop winder, a spindle and a tail stock relatively movable in axial direction, a carrier adapted to hold an empty tube and pivoted to swing the tube from a position at one side of the axis of said spindle into a position coaxial therewith, said carrier being mounted so as to be also movable parallel to the axis of said spindle, and

a magazine positioned adjacent said carrier and adapted to feed empty tubes to said carrier in succession.

5 2. In a cop winder, a spindle and a tail stock relatively movable in axial direction, a carrier adapted to hold an empty tube and pivoted to swing the tube from a position at one side of the axis of said spindle into a position coaxial therewith, said carrier being mounted so as to be also movable parallel to the axis of said spindle, and a magazine so connected with said carrier as to be movable therewith, said magazine being arranged to feed empty tubes to said carrier in succession.

10 3. In a cop winder, a spindle and a tail stock relatively movable in axial direction, a carrier adapted to hold an empty tube and pivoted to swing the tube from a position at one side of the axis of said spindle into a position coaxial therewith, said carrier being mounted so as to be also movable parallel to the axis of said spindle, means for swinging said carrier on its pivot comprising a slideable connection adapted to permit the movement of said carrier parallel to the axis 20 of said spindle without disturbing the effectiveness of said connection for transmitting said swinging movement, and a magazine positioned adjacent said carrier and adapted to feed empty tubes to said carrier in succession.

15 4. In a cop winder, a spindle and a tail stock relatively movable in axial direction, a feeler cone mounted at one side of said spindle so as to bear against the nose of the cop to feed it axially, said cone being rockably mounted so that it can swing away from said spindle, a cup mounted coaxially with said spindle and movable to engage the nose of the cop when said cone is swung away, to push the cop off the spindle, a carrier adapted to hold an empty tube and pivoted to swing the tube from a position at one side of the axis of said spindle into a position coaxial therewith, said carrier being mounted so as to be also movable parallel to the axis of said spindle, and a magazine positioned adjacent said carrier and adapted to feed empty tubes to said carrier in succession.

WILHELM REINERS.
